UNITED STATES PATENT OFFICE.

DUDLEY A. MULLANEY AND JOHNSON F. HENDRY, OF SCHENECTADY, NEW YORK,
ASSIGNEES TO GENERAL ELECTRIC COMPANY, A CORPORATION OF NEW YORK.

ELECTRODE FOR VACUUM TUBES.

Application filed July 8, 1925. Serial No. 42,274.

Our invention relates to improvements in electrodes for vacuum tubes, and more particularly to methods of constructing and supporting the grids and anodes used in such 5 devices.

It is the object of our invention to provide an electrode structure which shall not only be light and rigid but the parts of which will be symmetrical and consequently adapted for 10 rapid assembly in jigs, and fixtures so as to reduce manual assembling operations to a minimum.

In the manufacture of anodes and grids for space current devices, particularly of the 15 type known as power tubes in which the electrodes are of considerable size, it is customary to use heavy rods of molybdenum or tungsten for supporting the electrodes. These are usually riveted to the electrode body itself 20 and either welded or riveted to metal straps by means of which the assembled structure is clamped to some glass member of the tube, usually the stem through which the lead-in wires pass.

25 In accordance with our invention we use a lighter but equally rigid structure for uniting the parts of such electrodes as well as for holding the same in position in the tubes.

The structure is shown in detail in the 30 annexed drawing in which:

Fig. 1 shows our improved supporting structure as applied to an anode of a space current device.

Fig. 2 illustrates this application to a grid 35 or control electrode, and

Fig. 3 depicts a complete space current device embodying the improved electrode of our invention while

Fig. 4 is a detail of an anode.

40 The improved structure of the invention is applicable to different types of electrodes so that both anode and grid may, for example, be built along the same general lines.

Referring in detail to the drawings it will 45 be observed that the anode support of Fig. 1 is made from flanged or channel members 1-2, preferably rolled or stamped from sheet molybdenum or other suitable metal. These are attached to the anode sections, preferably 50 by riveting although they may be spot welded in place if desired. Each channel member has welded or riveted to it at the end opposite the anode one-half 5 or 6 of a metal clamp.

The two halves when placed together are 55 adapted to embrace the glass stem 30 or 34

of the tube in a manner shown in Fig. 3 where a portion of such a clamp is visible. For this purpose, the clamps are provided with holes 7, 8, 9, 10 for the reception of screws which are indicated in Fig. 3.

Fig. 4 illustrates a detail of the anode structure showing a method of constructing the anode in question so as to secure substantially the same bracing effects of the channel members 1 and 2 and thus additional 65 strength. In this case, the anode is composed of flat members 3, 4, 11, 12 provided with flanges 13 by means of which the members may be assembled by riveting or welding as desired.

Fig. 2 illustrates the application of the channel supports to the construction of a grid or control electrode. In this case the flanged or channel members are represented by 14, 15. These are attached to clamp members 5 70 and 6 in the same manner as the anode of Fig. 1, the clamps in this case serving the same purpose heretofore described for the anode.

The grid wire 17 is wound over the channel members, the latter being wide enough 80 so that the resulting cage will accommodate the filament or cathode which is shown at 18. The upper portions of the channel members 14, 15, are held together by means of bar 19 made of suitable insulating material such as 85 fused quartz which is embraced and held by the ends of the channel members in any appropriate way. This bar serves as a support for the cathode and wires 20 may be imbedded in the quartz and used to hold the cathode 90 supporting system which comprises insulating members 21 preferably made of fused quartz, spring 22 and retaining hooks 23.

Other metal supporting members may be held by the quartz cross-piece 19 to aid in 95 keeping the elements of the tube rigid. Thus, the end 24 of the leading-in conductor 32 which is sealed into the press 25 may extend beyond the press and rest in a bearing hole in the quartz bar 19. This facilitates assembly since the anode and cathode may be rapidly and accurately brought into their relative juxtaposition and rigidly held in place.

A conductor 33 may be wrapped around the wire 32 in any suitable manner and attached to one of the electrodes of the device, for example, the anode, and thus serve to connect the anode with the terminal 27.

Figure 3 shows the method by which the electrode and supports are disposed in a 110

space current device of the power tube type. The tube consists of a glass container 26 a portion of which is shown broken away. The anode 11 is also shown broken away in order 5 to expose the grid and cathode whose structure has been described in detail above. The cathode leading-in wires are indicated by 10 31, embedded in a glass press around which is clamped the grid support composed of 15 clamp members 5, 6. The filament conductors are brought out to terminal posts only one of which, 29, is shown, while the grid is connected to post 28 which together with post 29 are held together in insulating relation by the end caps 35. The upper end of the tube is surmounted by a contact cap 27 to which one of the electrodes e. g. the anode is connected as above described.

A reentrant glass tube 30 constituting a 20 part of the container 26 and terminating in a seal or press 25 is used for supporting the anode 11 by an intermediary of clamp members of which only one, 5, is shown in the drawing.

25 The electrode structure and supporting system described above is very rigid, easily produced and readily assembled. It is less liable to warp out of shape under the stresses produced by the heat evolved during the operation of the tube and presents the further 30 advantage of being adaptable to quantity manufacture and assembly in machines and jigs.

What we claim as new and desire to secure by Letters Patent of the United States, 35 is:—

1. A space current device comprising a container of insulating material, a reentrant glass tube at each end of said container, an 40 anode mounted on one of said reentrant tubes and a grid mounted on the other reentrant

tube, the supports of both anode and grid comprising flanged members metallically attached to and extending along the entire longitudinal axis of the surface of said anode 45 and grid, said anode and grid being provided with clamp members adapted when coacting with each other to embrace said respective reentrant glass tubes.

2. In a space current device, an anode comprising a plurality of alternately arranged flat and round portions provided with flanges which extend in a direction normal to the surfaces of said portions at their edges, said flanges being secured together to form a rigid 55 body of closed perimeter, and means for supporting the anode within the device, said means comprising a pair of oppositely disposed channel members secured to said flat anode portions.

3. In a space current device, a grid comprising a plurality of upright channel members about which the grid wire is wound, a clamp secured to one end of the channel members for supporting the grid within the 65 device, the opposite end of said members being spaced by an insulating material which is adapted to constitute an electrode support.

4. In a space current device, an evacuated envelope provided with a reentrant stem a 70 combined filament and grid electrode arrangement comprising a pair of upright channel members about which the grid wire is wound, said members being spaced by an insulating material at one end and terminating in a clamp at the other end which embraces said stem, a filament suspended between the insulating material and said stem.

In witness whereof, we have hereunto set our hands this 7th day of July, 1925.

DUDLEY A. MULLANEY.
JOHNSON F. HENDRY.
